UNITED STATES PATENT OFFICE.

OSWALD V. SERAFINI, OF BOSTON, MASSACHUSETTS.

WALL CONSTRUCTION.

Application filed April 27, 1925. Serial No. 26,186.

This invention relates to wall construction and particularly to methods of constructing partitions for closets in toilets and like places, and has for its object the provision of means whereby such partitions may quickly and economically be built and locked securely to the main walls and floors of the building.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings—

Figure 1 represents a horizontal section of a closet for toilets.

Figure 2 represents a side elevation of one wall thereof.

Figure 3 represents a front elevation of the same, and

Figure 4 represents a horizontal section of one wall of the closet drawn to an enlarged scale and showing the supporting structure thereof.

Similar characters indicate like parts throughout the several figures of the drawings.

In the drawings 10 is the wall of a room such as the toilet of an office building, and 11, 11 are two walls extending perpendicularly therefrom to form a closet, the door of which is adapted to be positioned between the faces 12, 12 on the aligned front ends 13 of said walls 11.

These walls 11 preferably never extend upwardly to the ceiling and therefore can have no support therefrom, and it is likewise true that the greatest part of the lower end of wall 11 is some distance above the floor 14 of the room, and therefore can have no support at this point from said floor.

As a consequence therefore there is considerable difficulty in constructing these walls rigidly by the usual methods now employed.

This is all the more difficult in closets where a terrazzo finish is desired.

By the construction herein shown and described the walls 11, may be built into the building as a permanent part thereof with a terrazzo finish over the entire face thereof, this finish being simply a continuation of the terrazzo finish of the wall of the room.

In carrying out the present method a plurality of vertical rods 15 are positioned in alignment a given distance from the wall 10 and are spaced apart as indicated in Fig. 4, with their lower ends securely embedded in the floor 14.

These rods 15 extend upwardly to the point where the top of the wall 11 will be when finished.

At stated intervals on these rods 15 are secured horizontal rods 16 by means of wire loops 17.

One of the rods 15 is centrally disposed between the faces 12, 12 and back of this central rod 15 are two vertical rods 18 aligned therewith, the lower ends of which are also embedded in the floor 14 and the upper ends are substantially where the top of the finished wall 11 is to be.

At a predetermined distance above the floor 14 are disposed two horizontal rods 19, the rear ends of which are embedded in the wall 10 while the front ends are secured to the rods 18, and also to the central rod 15 by wire loops 20.

To these vertical rods 18 and central rod 15 are secured the front ends of a plurality of other horizontal rods 22, the rear ends of which are anchored in the wall 10 in any well known manner.

Secured to the horizontal rods 19 and 22 are a plurality of vertical rods 23.

Where the rods intersect they are secured together by wire loops 23.

While the size of the rods and the distance apart they are spaced do not in any way affect the invention, it is preferred to

use $\frac{1}{4}$ inch cylindrical rods and space them apart nine inches on centers.

When the rods have all been positioned and wired together they are covered with metal laths 25 which are wired to said rods.

Cement plaster 26 is then applied to both sides of the structure thus formed and allowed to harden.

This cement plaster base has its corners 10 rounded as indicated at 24 in Fig. 4.

When the walls 11, 13, have been constructed in this manner a coating 27 of terrazzo is applied to the entire surface thereof, this coating being preferably about 15 three-eighths of an inch thick.

As the terrazzo is applied to the cement plaster 26 in dampened condition, it will adhere to said cement plaster and practically become a part thereof.

20 When the terrazzo coating 27 has hardened it is polished and otherwise finished to suit different conditions.

When completed the walls 11, 13, become a part of the building and as all corners at 25 intersections are curved, it is perfectly sanitary as there are no corners in which dirt may lodge.

Heretofore, it has been the practice to 30 cast slabs which are conveyed to the job and set in place by angle irons, screws, bolts and legs, which work consumes much time and is therefore very expensive to construct.

Moreover, such constructions leave many 35 corners in which dirt is liable to collect, thus making the same unsanitary.

When completed the front portion 13 of each wall 11 forms a solid support secured firmly to the floor 14 and by means of this 40 support and the intersecting rods extending therefrom to the wall of the room, the balance of the wall is rigidly supported.

It is obvious that the dimensions of the various elements and the composition of the ingredients used may be varied at will.

45 It will be noted that when these partition walls are completed the entire surface is continuous and free from cracks and joints in which germs might collect.

The surface of the walls when constructed 50 are ground while in place by machinery and hand labor, leaving a highly polished surface.

As far as is known no other method has ever been used in constructing the walls or 55 partitions in the manner shown and described with their front ends anchored in the floor of the room and their rear ends anchored in the wall of the room.

Moreover, it is believed to be entirely new 60 to grind the aggregate used in the construction of such walls after the same has been placed in position and united with the interior structure of said walls.

It is believed that the method of constructing such walls and many advantages

thereof will be fully understood without further description.

Having thus described my invention, I claim—

1. The combination of a plurality of alined vertical rods the lower ends of which are anchored in the floor of a building, other vertical rods alined perpendicular to the line of the first mentioned rods, horizontal rods secured to said vertical rods and certain of which have their ends anchored in the wall of a building, metal laths secured to said rods, an aggregate secured to opposite sides of the structure thus formed, and a continuous coating of terrazzo applied to the entire outer face of said aggregate. 75 80

2. The combination of a plurality of alined vertical rods the lower ends of which are anchored in the floor of a building, other vertical rods alined perpendicular to the line of the first mentioned rods with their lower ends spaced from said floor, horizontal rods secured to said vertical rods and certain of which have their ends anchored in the wall of a building, metal laths secured to said rods, an aggregate secured to opposite sides of the structure thus formed, and a continuous coating of terrazzo applied to the entire outer face of said aggregate. 85 90 95

3. The combination of a structure of horizontal and vertical rods wired together and anchored to the wall and floor of a building, a wall of aggregate formed thereon, and a coating of terrazzo applied to the outer surface of said wall of aggregate. 100

4. The combination of a structure of horizontal and vertical rods wired together and anchored to the wall and floor of a building; a wall of aggregate formed thereon with all intersecting corners curved; and a coating of terrazzo applied to the outer surface of said wall of aggregate. 105

5. The combination of a structure of horizontal and vertical rods wired together, said horizontal rods having ends extending into the wall of a building and anchored therein and certain of said vertical rods having their lower ends extending into the floor of said building and anchored therein; a wall of aggregate formed thereon; and a coating of terrazzo secured to the outer surfaces of said wall and forming a continuation of the surface of the building wall. 110 115 120

6. The combination of an open work structure permanently anchored to the floor and one wall of a building; a wall of aggregate formed thereon and supported thereby; and a coating of terrazzo secured to the outer surfaces of said aggregate wall and forming a continuation of the building wall. 125

7. The combination of a structure comprising a plurality of vertical members the lower ends of certain of which are anchored 130

in the floor of a building and a plurality of horizontal members tied to said vertical members and having their rear ends anchored in the wall of a building; a wire mesh secured to said structure; a wall of aggregate formed thereon and forming a continuation of the aggregate in the building

wall, and a continuous coating of terrazzo secured to the outer surfaces of the building wall and the wall of aggregate formed upon said structure.

Signed by me at 746 Old South Bldg., Boston, Mass., this 23rd day of April, 1925.

OSWALD V. SERAFINI.
